RUBBER HEEL

John F. Anderson, Chicago, Ill.

Application August 2, 1940, Serial No. 349,566

6 Claims. (Cl. 36—36)

This invention is directed to an improvement in means for securing a rubber heel to a shoe, and is filed as a continuation in part of my application filed December 4, 1939, Serial No. 307,497.

5 The primary object of the invention is the provision of means whereby the heel may conveniently and simply be secured in place with respect to the shoe through the use of few parts and with minimum mechanical operation.

10 The invention is illustrated in the accompanying drawing in which

15 Figure 2 is a section on the line 2-2 of Figure 1 showing the securing plate in its initial or arched position;

Figure 3 is a similar view showing the plate in final or flattened position;

20 Figure 4 is an inverted sectional view showing a modified form of securing means;

Figure 5 is an inverted perspective view of the form shown in Figure 4.

Figure 6 is a section on the line 6—6 of Figure 4.

ticularly Figures 1, 2 and 3, the rubber heel is of substantially horse-shoe form, with the inside surface extending through the for-

terior open portion 2 extending through the forward portion of the heel. A heel carrying plate

3 is designed to be fixed in any appropriate manner to the sole 4 of the shoe or the bottom of the boot of a woman's shoe. The plate 3 has

the heel of a woman's shoe. The plate 3 has an outline shape corresponding closely to that of the heel, and is provided with an upstanding edge flange 5, the upper edge of which is inturned to present a pointed relatively narrow spur edge 6.

The outer edge of the heel 1 is formed at an appropriate point with a recess 7 to define a line with which the spur 6 will engage. The inner margin of the heel is formed with a shoulder 8 at a point about mid-height the inner wall of the heel, the lower edge of the heel below the shoulder 8 being of slightly greater thickness transverse the heel, as at 9, than that portion of the heel above the shoulder.

A nut 10 is welded or otherwise secured to the heel plate 3 about centrally of the length and width thereof, or the plate 3 may be formed with a threaded opening in lieu of a nut, as shown in Figure 3. A securing plate 11 is of a form to fit within the inner wall of the heel, with its margin seated on the shoulder 8. This securing plate 11 is normally of slightly arch form, that

is, when its edges are first placed on the shoulder 8, plate 11 assumes the position indicated in Figure 2.

The plate 11 is formed with a central opening 12 and a bolt 13 is provided to pass into this opening and to engage the appropriately located nut 19, carried by the plate 3, or a threaded opening shown in Figure 3. The outer end of the bolt has a fixed head 14, by which the said bolt may be manipulated to engage the nut. 10

In this form of the invention, the plate 3 is secured to the sole 4, and the heel 1 is slid longitudinally into the plate 3, being engaged entirely around the heel, except at the forward edge, within the flange 5 and spur 6 of the plate. The securing plate 11 is then seated on the shoulder 8, and when so applied, the opening 12 in the plate 11 will be in alignment with the nut 10. The bolt 13 is then passed through the hole 12 and engaged in the nut 10, or threaded opening, as the case may be, and the bolt is tightened through the medium of the fixed head 14 until the normally arched plate 11, as shown in Figure 2, is forced into a flattened position, as shown in Figure 3. This operation of the securing plate 11 not only clamps the enlarged portion 9 of the inner wall of the heel onto the plate 3, but spreads the heel proper laterally so as to provide a secure interfit between the flanges 5 and the spur 6. The heel is thus fixedly secured in position in a simple expeditious manner which will permit convenient renewal of the heel when the latter is worn and to be replaced.

In Figures 4 and 5, the heel here indicated at 15 is of more solid form and appropriate outline. The heel is formed with a central well 16 of materially less depth than the corresponding dimension of the heel. The juncture of the rear wall 16^a and the bottom of the well is bevelled at 16^b and correspondingly the junction of the side walls and bottom of the well are bevelled at 16^c, the front wall of the well being vertical as at 16^d. With this form of heel, there is provided a sole carrying plate 17 having upstanding edge flange 18 and inturned spur 19 similar to the form first described, the flange and spur cooperating with the heel as in the previous form. A securing plate 20 is designed to fit snugly in the well 16 and is formed with a central opening 21. The securing plate corresponds substantially to the shape of the well and is slightly arched in cross section, as shown in Figure 6. The side and rear edges of the plate are beveled as at 16^d to correspond with the beveled portions 16^b and 16^c of the well walls. A threaded bolt 55

22 is passed through the opening 21 and engages a nut 23 carried by and secured to the plate 17, the bolt having a fixed head 24, through which the bolt may be manipulated in engagement with the nut 23. Of course, it is to be understood, a threaded opening in the plate may be used in lieu of the nut.

The tightening of the bolt forces the plate 20 into pressure contact with the rubber heel 10 at the bottom of the well 16, with a tendency to spread that portion of the heel beyond the margin of the well and so afford an intimate holding contact of the heel and plate 17 in addition to the securing effect of the bolt and nut.

15 By the construction described, the rubber heel can readily and quickly be replaced, at the same time the means employed to fasten the heel to the shoe is such and is so located that the recess in the surface of the heel acts to create a grip when the heel is in use. This is particularly true in the form shown in Figures 4 and 5. The recess there shown acts to create a vacuum, hence a grip when the heel is in use.

What is claimed as new is:

25. 1. A renewable heel structure, including a plate adapted for permanent attachment to the heel portion of a shoe and having an exterior contour corresponding to a shoe heel, a flange extending substantially at right angles from the side and rear peripheral portions of the plate, a bead projecting inwardly from the free edge of the flange, a removable rubber heel having a contour corresponding to said plate, said rubber heel having an external groove for said bead, and rigid means carried by said plate and engaging said rubber heel in spaced relation to the flange whereby to resist inward flexure of

the sides and rear of the peripheral portion of the rubber heel.

2. The structure of claim 1, wherein the rubber heel is recessed on its longitudinal center line, and the rigid means includes a metal plate 5 spanning the recess.

3. The structure of claim 1, wherein the rubber heel is recessed with the recess open at the front and the rubber is of horse-shoe form, and the rigid means includes a metal plate spanning 10 the recess and having screw connection with the first plate.

4. The structure of claim 1, wherein the wall of the recess is formed with a beveled shoulder and the rigid means is formed with a beveled 15 edge to cooperate with the beveled shoulder.

5. The structure of claim 1, wherein the wall of the recess is shouldered, and the rigid means includes a metal plate spanning the recess and having beveled edges to engage the beveled edges 20 of the shoulder.

6. A renewable heel structure, including a plate adapted for permanent attachment to the heel portion of a shoe and having an exterior contour corresponding to a shoe heel, a flange extending substantially at right angles from the side and rear peripheral portions of the plate, a bead projecting inwardly from the free edge of the flange, a removable rubber heel having a contour corresponding to said plate, said rubber 30 heel having an external groove for said bead, and a shouldered recess, a metal plate engaging the shoulder in the recess, and means cooperating with the metal plate for spreading the rubber heel toward the said means and the flange 35 to lock the plate and heel together.

JOHN F. ANDERSON.
